UNITED STATES PATENT OFFICE

2,095,830

STARTING CIRCUIT FOR ELECTRIC DIS-
CHARGE LAMPSJustin Peterson, Lynn, Mass., assignor to Gen-
eral Electric Company, a corporation of New
York

Application August 14, 1936, Serial No. 96,067

4 Claims. (Cl. 176—124)

My invention relates to electric discharge lamps, and more specifically to an improved starting circuit for such lamps.

One object of my invention is to provide an auxiliary power source for multiple connected discharge lamps whereby a starting action under normal operating voltages is obtained within substantially the same time periods as is obtainable in series connected lamps at starting voltages considerably higher than the operating voltage.

For a better understanding of my invention, together with other and further objects thereof, reference is had to the following description, taken in connection with the accompanying drawing, and its scope will be pointed out in the appended claims.

In the accompanying drawing, I have illustrated diagrammatically, an electric discharge lamp 1 provided with electrodes comprising anodes 2 and 3 and cathodes 4 and 5, each of the pairs being capable of functioning alternately as anode and cathode during operation. This type of lamp is described in greater detail in U. S. Patent 1,971,907 Found, issued August 28, 1934. The transformer 6, provided with a primary winding 7 and a secondary winding 8, is connected to the ends of cathodes 4 and 5 respectively by conductors 9 and 10. The other end of the cathode 4 is connected to its anode 2 and correspondingly the other end of the cathode 5 is connected to its anode 3. A circuit outside of the lamp is established by my improved starting circuit during the starting period only. This circuit includes in accordance with my invention an auxiliary winding 11 of the transformer 6 and a thermal switching device 12, which establishes this circuit for a predetermined time beginning at the moment current is supplied by the secondary winding 8. The switching device 12 includes an operating magnet 13 energized by an auxiliary winding 14 through conductors 15 and 16 whenever current flows in the primary winding 7. A switching arm or armature 17 is attracted to one operating position by the magnet 13 when it is energized and is moved to a second operating position by a spring 18 when the magnet is deenergized. In the second position the arm 17 establishes a circuit through the starting winding 11. This circuit may be traced from the secondary winding 8 to conductor 9, cathode 4, anode 2, conductor 19, winding 11, conductor 20, contact arm 21, contact 22, conductor 23, a thermal element 24, conductor 25, anode 3, cathode 5, conductor 10 and back to the secondary winding 8.

In this circuit, therefore, the secondary winding

8, and the starting winding 11, supply current to the cathodes 4 and 5 in series.

In the operation of multiple connected discharge lamps, the internal impedance of the transformers does not permit a substantial rise of the voltage over the normal operating voltage during the starting period. The starting of the lamps is therefore not as certain, or in other words, does not take place within the same time periods as is the case in series operated lamps where a starting voltage considerably higher than the operating voltage is obtainable. In accordance with my invention, I provided the auxiliary power source as above described which supplies an additional power for heating the cathodes of the lamps so that the substantially normal operating voltage will be capable of starting the lamps, within a time period substantially the same as is required for the same lamps when series connected and at substantially higher starting voltages. In the apparatus illustrated, for example, the normal operation current is 6.6 amperes. During the starting period when the auxiliary coil 11 is connected in series with the secondary winding 8 a current of 7.8 amperes is obtainable. The time for which the thermostat 24 is set to operate is about 25 to 30 seconds, which is substantially the same setting that is used for series operation at which a contact current of 6.6 amperes is maintained but in which the voltage rises as much as 500% above the operating voltage to start the lamps.

The thermostatic element 24 is provided with a tongue 26 which moves under a pin 27 attached to the armature 17 and thereby prevents this armature from moving to its second position responsive to the attraction of the magnet 13. The flow of current through the element 24, however, causes it to warp and move the tongue 26 away from the pin 27 after a predetermined interval, whereby the circuit through the cathodes is broken and the voltage of the secondary winding 8 is placed across the gap of the electrodes within the lamp. The time period of heating the electrodes, 25 to 30 seconds in the illustrated example, is so arranged that the electrodes are sufficiently heated and a discharge between the electrodes is started when the magnet is deenergized. A subsequent interruption of power, however permits the armature 17 to move to its previous position in response to the action of the spring 18, so that upon a resumption of power the above operation is repeated.

With this improved arrangement of the elements I am, therefore, able to start discharge

lamps in multiple with substantially no rise in voltage with the same certainty and within the same time periods as is possible with series operation in which high starting voltages are available.

5 What I claim as new and desire to secure by Letters Patent of the United States, is:

1. In a starting circuit for electric discharge lamps, the combination of a gaseous discharge lamp provided with a thermionic cathode, a co-operating anode, a transformer winding having its ends connected respectively to the said anode and one end of said cathode, an auxiliary transformer winding connected between the other end 10 of said cathode and said anode energized simultaneously with said first transformer winding, and a time delay switching means for disconnecting said auxiliary transformer winding a predetermined time interval subsequent to the beginning 15 of current flow in said first transformer winding.

2. In a starting circuit for a gaseous discharge lamp, the combination of a discharge lamp provided with a pair of thermionic electrodes including metallic filaments and operable alternately as anode and cathode, a transformer winding connected to one end of each of said filaments, a second transformer winding arranged to increase the heating current for said cathodes during the starting period and connected between the other ends of said filaments, and a time delay device arranged to establish a circuit through said electrodes and said two transformer windings at the interruption of current through said first transformer winding and to interrupt said circuit through said second winding a predetermined period after each energization of said first wind-

ing whereby the voltage of said first winding is available to start a discharge between said electrodes.

3. In a starting circuit for electric discharge devices, the combination of an electric discharge device provided with a thermionic cathode, a co-operating anode, a transformer winding having its ends connected respectively to said anode and one end of said cathode, an auxiliary transformer winding connected between the other end of 10 said cathode and said anode energized simultaneously with said first transformer winding, and a time delay switching means for disconnecting said auxiliary transformer winding a predetermined time interval subsequent to the beginning 15 of current flow in said first transformer winding.

4. In a starting circuit for a gaseous discharge device, the combination of a discharge device provided with a pair of thermionic electrodes including metallic filaments and operable alternately as 20 anode and cathode, a transformer winding connected to one end of each of said filaments, a second transformer winding arranged to increase the heating current for said cathodes during the starting period and connected between the other 25 ends of said filaments, and a time delay device arranged to establish a circuit through said electrodes and said two transformer windings at the interruption of current through said first transformer winding and to interrupt said circuit 30 through said second winding a predetermined period after each energization of said first winding whereby the voltage of said first winding is available to start a discharge between said electrodes.

JUSTIN PETERSON.
